UNITED STATES PATENT OFFICE.

WILLIAM HENRY HOWARD, OF PUEBLO, COLORADO.

PROCESS OF DESILVERIZING LEAD BULLION.

SPECIFICATION forming part of Letters Patent No. 563,769, dated July 14, 1896.

Application filed July 27, 1895. Serial No. 557,317. (No specimens.)

To all whom it may concern:

Be it known that I, WILLIAM HENRY HOWARD, a citizen of the United States, residing at Pueblo, in the county of Pueblo and State of Colorado, have invented certain new and useful Improvements in Desilverizing Lead Bullion; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to metallurgy, and its object is to facilitate and cheapen the process of treating zinc-silver crusts in the desilverization of lead bullion.

In what is known as Parkes's process for 20 effecting this result, zinc is stirred into the molten argentiferous lead, forming an alloy or crust, which rises to the surface. This crust is of mushy consistency, and consists of zinc and silver and gold in granular form, 25 saturated with a large excess of lead, only a small portion of which is combined with the alloy, the greater portion being mechanically mixed therewith. To liqueate the excess of lead in the crust when skimmed off, this alloy 30 is sweated in an iron pot or in a reverberatory or other furnace, additional heat being applied in each case. Inasmuch as the melting-point of the mechanically-mixed pure lead is lower than that of the alloy, the former melts 35 and drains out of the crust by gravity. This method, however, removes only a comparatively small amount of lead, because much of it seems to be entangled in the crust and will not drain out. The crust when dry still contains from seventy-five to eighty per cent of 40 lead, which must be handled and treated in the subsequent retorting and cupelling processes by which the zinc, the gold, and the silver are extracted from the crust.

45 My invention relates especially to the treatment of the crust for the purpose of getting it drier; that is to say, free from lead, the object being to save time, reduce the quantity of material to be handled, and bring it into 50 better condition for treatment in the retorts. I also aim to dispense with the furnace or ket-

ties for heating the crust, so that the operation can be performed more economically as well as more quickly.

My improvement consists in subjecting the 55 crust to pressure, whereby the unalloyed lead is squeezed out before it has time to cool and harden. Incidentally, the heat resulting from the pressure may assist in keeping the lead liquid. By this method I am able to dispense with all additional external heat and 60 effect a great saving in time. Moreover, I get rid of a much greater quantity of lead, so that the resulting bullion is not only considerably reduced in weight and bulk and therefore easier to be cupelled, but it runs fifty 65 per cent higher in silver.

My improvement can be carried out in various ways.

In the accompanying drawings, Figure 1 70 shows in section a desilverizing-kettle and a liquating screw-press. Fig. 2 is a plan of the same. Fig. 3 is a modification. Fig. 4 is a sectional elevation of a press arranged to be kept hot by the lead in the kettle. Fig. 5 75 shows a device for operating such a press by fluid pressure.

The iron kettle A, which holds the melted 80 argentiferous lead B, is of the usual shape and size. Adjacent to this kettle I provide a press, preferably comprising a cylinder C, supported on a suitable foundation D and having perforations c in its bottom or in the lower portion of its walls, or both, and containing a piston E. Any desirable means 85 may be adopted for operating the piston, such as a screw F, working in a nut G formed in or attached to a heavy yoke G' spanning the cylinder. The screw is provided with arms f, or the like, for turning it. Under the cylinder is placed a trough H, inclined toward 90 and terminating over the kettle A. The zinc crust b is removed from the surface of the lead by any suitable means, such as a hand-skimmer or the skimmer and sweater patented by me July 25, 1893, No. 502,122. While still hot and mushy it is put into the cylinder and compressed by the piston. The 95 squeezed-out lead drains through the perforations c and runs back into the kettle. The operation can be very quickly performed before the crust has time to get cool. The 100

pressed and dried cake is then taken out of the cylinder to be broken up and sent to the retorts. To eject the cake from the cylinder a false bottom C' may be used, provided with 5 lifting-rods c' at two or more points; or the press may be mounted on a truck I adapted to be rolled back on an elevated track, as K, from its position over the stationary trough II, the bottom of the press being hinged or 10 otherwise removable, so that it can be dropped down, as shown in dotted lines, to release the cake of crust.

If desired, the cylinder of the press can be placed in the molten lead in the kettle, as 15 shown in Fig. 4. This arrangement utilizes the heat of the lead B to keep the crust hot and liqueate the unalloyed lead therein.

The entire press may be suspended from an overhead carrier L, and by suitable mechanism, such as cable M, it can be lowered 20 into the kettle.

When the operation of compressing the alloy is complete, the press is hoisted, run away from the kettle, its bottom removed, 25 and the cake forced out of the cylinder and dropped on the floor, where it can be broken up ready for the retorts.

When convenient, fluid pressure, such as 30 steam or compressed air, may be used to effect the pressing or the hoisting, or both. Fig. 5 shows one form of apparatus for utilizing fluid pressure for these purposes. The cylinder N carries a yoke O, from which is hung the cylinder C. In the cylinder N is a 35 piston P, whose rod p is attached to and actuates the piston E of the press. Hose R lead the fluid pressure to ports above and below the piston P, being controlled by a cock r. In the upper part of the cylinder N is a piston 40 S, whose rod s is hung to the overhead carrier. A hose R' leads air or steam into the cylinder above the piston S when the press is to be hoisted.

If desired, the fluid pressure can be applied 45 directly to the surface of the alloy—for instance, by admitting it to the cylinder below the piston E or some other tightly-fitting cover or lid.

It is evident that many other modifications 50 of the apparatus can be devised without departing from the spirit of my invention.

Having thus described my invention, what

I claim, and desire to secure by Letters Patent, is—

1. As an improvement in Parkes's process 55 of desilverizing lead bullion, subjecting the zinc crust to pressure after removing it from the desilverizing-kettle, substantially as described.

2. The process of liquating zinc crusts 60 formed in the desilverization of lead bullion, which consists in subjecting said crusts to pressure without the application of heat, substantially as described.

3. The process of liquating zinc crusts 65 formed in the desilverization of lead bullion, which consists in collecting said crusts adjacent to the lead in the desilverizing-kettle and there subjecting them to pressure to squeeze out the unalloyed lead, substantially 70 as described.

4. The process of liquating zinc crusts 75 formed in the desilverization of lead bullion, which consists in collecting said crusts, immersing them in the lead in the desilverizing-kettle, and subjecting them to pressure to squeeze out the unalloyed lead, substantially 80 as described.

5. The combination with a desilverizing-kettle for the production of zinc crusts from 85 lead bullion, of a press, and means for moving said press to and away from said kettle, substantially as described.

6. In apparatus for the desilverization of 90 lead bullion, the combination with the desilverizing-kettle, of a press comprising a cylinder having a perforated bottom, and means for lowering said press into said kettle, and raising it therefrom, substantially as described.

7. In apparatus for the desilverization of 95 lead bullion, the combination with a desilverizing-kettle, of a press comprising a cylinder having a perforated bottom, means for raising and lowering said press, and means for conveying it to and from a point above said kettle, substantially as described.

In testimony whereof I affix my signature in presence of two witnesses.

WILLIAM HENRY HOWARD.
